UNITED STATES PATENT OFFICE.

THOMAS HENRY SINCLAIR, OF HAMILTON, ONTARIO, CANADA.

CLAMP FOR CONCRETE-FORMS.

1,354,516.

Specification of Letters Patent.

Patented Oct. 5, 1920.

Application filed January 26, 1920. Serial No. 354,230.

To all whom it may concern:

Be it known that I, THOMAS HENRY SINCLAIR, of the city of Hamilton, in the county of Wentworth, Province of Ontario, Dominion of Canada, have invented certain new and useful Improvements in Clamps for Concrete-Forms, of which the following is the specification.

My invention relates to improvements in clamps for concrete forms, and the object of the invention is to devise a clamp that can be readily applied to any particular form with the minimum of trouble, and which will be retained in place when so applied. A further object is to construct a clamp which will have a bearing on the form around its entire surface, and a still further object is to provide a clamp which will be adjustable and which can be tightened on being applied to the form.

My invention consists of a lower clamp portion serrated on its upper surface and provided with a plurality of lugs extending outwardly from its side surfaces, said lower clamp portion having a slot extending longitudinally of the same intermediately of its length, an upper clamp portion having a suitable recessed depending end and serrations on the lower side of such upper clamp portion adapted to engage the serrations on the upper face of the lower clamp portion, said upper clamp portion having a slot extending longitudinally of the same intermediately of its length and adapted to register with the aforesaid slot in the lower clamp portion when both portions are in position, a chain connected at one end to the lower clamp portion and adapted to be adjustably secured at the other end in the recessed end of the upper clamp portion, said upper clamp portion having lugs extending outwardly from the sides thereof, a lever adapted to be inserted in between the lugs of the upper and lower clamp portions for adjusting the same relatively to one another, and means extending through the registering slots in the upper and lower clamp portions for securing the clamp to a batten of the concrete form, all as hereinafter more particularly described and illustrated in the accompanying drawing in which:—

Figure 1 represents a horizontal section of a concrete form, showing a clamping device constructed according to my invention applied thereto.

Fig. 2 is a longitudinal section through both portions of the clamp.

Fig. 3 is a plan view thereof, and
Fig. 4 is a cross section.

Like characters of reference indicate corresponding parts in the different views.

1 is a concrete form, preferably, constructed of wood, and, in the present instance, carrying the battens 2 which are beveled off at their ends as is shown in Fig. 1. 3 is the lower clamp portion having a slot 4 extending longitudinally of the same intermediately of its length and provided on its upper face with the serrations 5. 6 are a plurality of lugs extending outwardly from the side faces of such lower portion.

7 is a ring formed on one end of the lower portion to which is secured a chain 8. 9 is the upper clamp portion having a slot 10 extending longitudinally of the same intermediately of its length and provided with a plurality of lugs 11 extending outwardly from the top of such portion. 12 is the depending end of the upper clamp portion having a recess 13 with a confined neck-shaped entrance 14 adapted to receive the other end of the chain.

15 are serrations on the lower face of the upper portion 9 adapted to engage the aforesaid serrations 5 upon the upper clamp portion being applied to the lower clamp portion. 16 is a nail adapted to extend through the slots 4 and 10 and to secure the clamp to a batten 2, and 17 is a lever for moving the clamp portions relatively to each other for tightening up the chain.

The operation of the device is as follows: The chain 8 is applied to the battens 2 as shown in Fig. 1, the free end of the chain being inserted in the recess 13 of the end 12 in such position as to hold the chain as tightly as possible around the battens by hand. The upper clamp portion 9 is now applied to the lower portion 3, the serrations 5 engaging the serrations 15. The lever 17 is now inserted in a suitable manner between the lugs 11 and the lugs 6 as is clearly shown in Fig. 2. By exerting pressure on the lever in the direction of the arrow in Fig. 2, the portions are moved relatively to one another thus tightening up the chain 8 so that it has a bearing on the battens 2 throughout the entire periphery of the form. The nail or screw is now driven through the slots 10 and 4 into the batten 2 as is shown in Fig. 1 thus holding the clamping device in position and preventing its displacement.

It is understood that a plurality of these

clamping devices are used, the number depending upon the length of the form.

To release the device all that is necessary to do is to remove the nail or screw, insert 5 the lever and release the serrations 15 on the upper portion out of engagement with the serrations 5 on the lower portion.

From the above description it will be seen that I have devised a clamp for concrete 10 forms that will be simple and effective in use and which can be readily applied and adjusted with the minimum of labor.

What I claim as my invention is: -

1. In a clamping device for concrete 15 forms, the combination with the form, of upper and lower clamp portions engaging each other, a member connected at one end to the lower portion and at the other end to the upper portion, said member encircling 20 the form, means for altering the relative position of the clamp portions to each other for tightening the member encircling the form, and means for retaining the clamp portions in engagement with each other, said 25 means extending through the clamp portions and securing the same to the form.

2. In a clamping device for concrete forms, the combination with the form, and battens secured thereto and beveled off at 30 their ends, the bevel of the adjacent ends of the battens being in the same plane, of upper and lower clamp portions engaging each other, a member connected at one end to the lower portion and at the other end 35 to the upper portion, said member encircling the wood battens, means for altering the relative position of the clamp portions to each other for tightening the member encircling the form, and means for retaining 40 the clamp portions in engagement with each other said means extending through the clamp portions and securing the same to the battens.

3. In a clamping device for concrete 45 forms, the combination with the form, of upper and lower clamp portions respectively serrated on their lower and upper faces, such serrations adapted to be in engagement with each other, a chain encircling the form, connected at one end to the lower clamp portion 50 and at the other end adjustably connected to the upper portion, lugs on the sides of the upper and lower clamp portions, and a fork shaped lever inserted between the respective 55 lugs.

4. In a clamping device for concrete forms, the combination with the form, and battens beveled off at their ends, the bevel of the adjacent ends of the battens being in 60 the same plane, of upper and lower clamp portions respectively serrated on their lower and upper faces, such serrations adapted to be in engagement with each other, a chain encircling the batten, connected at one end

to the lower clamp portion and at the other 65 end adjustably connected to the upper portion, lugs on the sides of the upper and lower clamp portions and a fork shaped lever inserted between the respective lugs.

5. In a clamping device for concrete forms, 70 the combination with the form, of upper and lower clamp portions engaging each other, and each having a slot extending longitudinally of the same and intermediately of the length of the same, said slots coinciding in 75 the engaged position, means extending through the slots for securing the upper and lower clamp portions to the form, and a chain connected at one end to the lower portion and at the other end to the upper 80 portions and encircling the form.

6. In a clamping device for concrete forms, the combination with the form and battens beveled off at their ends, the bevel of the adjacent ends of the battens being in the 85 same plane, of upper and lower clamp portions engaging each other, and each having a slot extending longitudinally of the same and intermediately of the length of the same, said slots coinciding in the engaged position, 90 means extending through the slots for securing the upper and lower clamp portions to the batten, and a chain connected at one end to the lower portion and at the other end to the upper portion and encircling the batten. 95

7. In a clamping device for concrete forms, the combination with the form, of upper and lower clamp portions, serrations in the lower face of the upper portions and the upper face of the lower portion, said serrations 100 adapted to engage each other, lugs on the sides of the upper and lower portions, said portions each having a slot extending longitudinally therethrough intermediately of the length of the same, a lever, and a chain secured at one end to the lower portion and adjustably secured at the other end to the upper portion and encircling the form.

8. In a clamping device for concrete forms, the combination with the form, and battens 110 beveled off at their ends, the bevel of the adjacent ends of the battens being in the same plane, of upper and lower clamp portions, serrations in the lower face of the upper portions and the upper face of the 115 lower portion, said serrations adapted to engage each other, lugs on the sides of the upper and lower portions, said portions each having a slot extending longitudinally therethrough intermediately of the length 120 of the same, a lever, and a chain secured at one end to the lower portion and adjustably secured at the other end to the upper portion and encircling the batten.

THOMAS HENRY SINCLAIR.
